(57) **CLAIM**

The ornamental design for a media player display screen with graphical user interface, as shown and described.

DESCRIPTION

FIG. 1 is a front view of an embodiment of a media player display screen with graphical user interface according to the present disclosure showing a first image in an animated sequence;

FIG. 2 is a second image thereof;

FIG. 3 is a third image thereof;

FIG. 4 is a fourth image thereof;

FIG. 5 is a front view of another embodiment thereof showing a first image in an animated sequence;

FIG. 6 is a second image thereof;

FIG. 7 is a third image thereof; and,

FIG. 8 is a fourth image thereof.

The appearance of the transitional image sequentially transitions between the images shown in FIGS. 1-4 in the first embodiment, and FIGS. 5-8 in the second embodiment. The process or period in which one image transitions to another forms no part of the claimed design.

The dashed broken lines illustrate portions of the graphical user interface and form no part of the claimed design. The dot-dash lines illustrate the display screen and a boundary and form no part of the claimed design.

1 Claim, 8 Drawing Sheets
